UNITED STATES PATENT OFFICE.

ARTHUR A. GIRARD, OF HYDE PARK, MASSACHUSETTS.

CURTAIN-HOLDER.

1,099,034.

Specification of Letters Patent: Patented June 2, 1914.

Application filed January 3, 1913. Serial No. 740,017.

To all whom it may concern:

Be it known that I, ARTHUR A. GIRARD, a citizen of the United States, residing at Hyde Park, in the county of Suffolk and State of Massachusetts, have invented new and useful Improvements in Curtain-Holders, of which the following is a specification.

This invention relates to a device for fastening shades to shade rollers; and it has for its primary object the provision of a device of this character which may be readily connected with the roller and shade and associated with the latter in a manner which will positively eliminate any tearing thereof during the rolling or unrolling operation.

A still further object of the invention is to provide a device of this character which may be connected with the roller at a single point in the length thereof and which will include companion side gripping bars adapted to yieldingly contact with the shade at the opposite sides of the roller and in such manner as will positively prevent any longitudinal creeping of the shade on the roller.

Another object of the invention is the provision of a strip of yieldable material which may be associated with the fastener and roller respectively so as to maximize the frictional contact of the fastener with the shade.

With these and other objects in view, the invention consists of certain novel features of construction, combination and arrangement of parts, as will be hereinafter described and claimed.

In the accompanying drawings:—Figure 1 is a perspective view of a shade roller, showing the application of a fastener thereto; Fig. 2 is a longitudinal section through a portion of the roller; Fig. 3 is a transverse section therethrough; Fig. 4 is a view similar to Fig. 3, showing a slightly modified form of the invention; and Fig. 5 is a perspective view of the fastener.

The fastener is constructed preferably from a single length of spring wire which is bent in its main length to provide aligned loops 1 having an integral longitudinal gripping and connecting portion 2 and aligned terminals 3, the latter also forming gripping portions to assist in the action of the portion 2 to effectually hold the shade in an applied position upon the roller. The terminals 3 are separated relatively at 4 so

as to render the roller embracing loops 1 yieldable in a lateral direction relatively, so as to permit the device to readily conform with any lateral irregularities or imperfections in the surface of the roller. The connecting portion 2 is extended directly into the adjacent portions of the loops while the terminals 3 are slightly offset as at 5 from the adjacent portions of the loops for a purpose to be hereinafter referred to.

In applying the fastener to the roller whereby to hold the shade in an operative position thereon the attached terminal of the shade is partly wound around the roller 6 herein illustrated and a short strip 7 of elastic material is also partly wound around the roller and provided with a protecting terminal 8 which is free from the roller and which is adapted to overlie an adjacent portion of the fastener when the shade is partly wound around the roller. The loops 1 are substantially of U-configuration and are adapted to circumferentially embrace the roller and to yieldingly contact with adjacent portions of the shade, while the bar 2 and the terminal 3 of the fastener are extended in a longitudinal direction against the sides of the roller, so that under the inherent elasticity of the loops, the required purchase of said portions 2 and 3 will be obtained against the shade so as to hold the latter in its attached condition. The offset portions 5 of the loops present the terminals 3 in effective contact with the shade at the immediate terminal 9 of the material 7 and in such proximity with the free portion 8 of said material so that when the latter entirely circumscribes the roller it will be projected over said terminals 3 so as to extend across the joint 4 between the terminals and thereby relieve the winding of the shade of obstructions where they pass over the fastening. Said yieldable material 7 also serves to reinforce the shade at the points of engagement of the fastener therewith so as to insure against any accidental tearing of the shade, as will be apparent. The loops 1 under their inherent elasticity tend to indent the roller circumferentially, as shown at 10 in Fig. 2, so that portions of the shade will become engaged in the indentations thus formed, to thereby render the shade fixed against longitudinal shifting on the roller.

In the modified arrangement of the invention shown in Fig. 4, the flexible material 11 embraces the roller in such manner that

the free terminal 12 of said material underlies the continuous gripping bar 13 of the fastening 14. This form of fastener is otherwise identical in construction with the 5 first described form.

A single fastening device as described may be used immediately between the ends of the roller and associated with the shade in such manner as will hold the same effectually 10 in applied position and against being torn, as it is wound or unwound from the roller.

From the foregoing description, taken in connection with the accompanying drawings, the construction and operation of the 15 invention will be readily understood without requiring a more extended explanation.

Various changes in the form, proportion and the minor details of construction may be resorted to without departing from the 20 principle or sacrificing any of the advantages of this invention, as claimed.

Having thus described my invention, what I claim is:—

1. A shade fastener for shade rollers comprising a single length of springy wire bent in its main length to provide aligned embracing loops adapted to extend partly around the roller, connecting gripping portions connecting the loops with each other, one terminal of each of the loops being offset to-

ward the center of the loop and adapted to engage the roller, the said terminals being then extended toward each other and at right angles to their respective loops and parallel with the connecting gripping portion the said extended terminals providing a companion gripping portion and separated relatively thereby to render the loops yieldable laterally. 35

2. A shade fastener for shade rollers a 40 member having embracing loop portions extending partly around the roller and each having one of its terminals offset toward the center of the loop and bearing against the roller, the said terminals then being extended toward each other and at right angles to said loops and providing a gripping portion, a second gripping portion connecting the loops together and extending parallel with the first mentioned gripping portion, 45 and a strip of material associated with the roller and underlying the companion gripping portion.

In testimony whereof I affix my signature in presence of two witnesses.

ARTHUR A. GIRARD.
